[54] ELECTROSTATIC PROCESS
DEVELOPMENT APPARATUS[76] Inventor: Joan Helen Hull, Elmgrove Plant,
Rochester, N. Y. 14550

[21] Appl. No.: 729,623

[22] Filed: Oct. 5, 1976

[51] Int. Cl.² ..... G03G 15/09[52] U.S. Cl. ..... 118/658; 355/3 DD;
427/18

assembly for forming a magnetic developing brush which can be supplied with and carry a developer mix in a development region. The magnet assembly includes a plurality of curved, sector shaped magnets for carrying the mix to and from the development region and a rectangular cross-sectional magnet of greater magnetic force at the development region.
